United States Patent Office

Des. 179,348
Patented Dec. 4, 1956

179,348

AIRPLANE

Clarence L. Johnson, Encino, Calif., assignor to Lockheed
Aircraft Corporation, Burbank, Calif.

Application April 22, 1954, Serial No. 30,122

Term of patent 14 years

(Cl. D71—1)

Des. 179,348

PAGE 2

Figure 1 is a top plan view of an airplane showing my new design;

Figure 2 is a side elevational view thereof;

Figure 3 is a front elevational view thereof;

Figure 4 is a perspective view from the side and above thereof;

Figure 5 is a perspective view from the side and below thereof;

Figure 6 is a perspective view from the side and rear thereof.

The landing gear is shown in retracted position in Figs. 4, 5 and 6.

The essential features of my design reside in the portions shown in full lines.

I claim:

The ornamental design for an airplane, as shown and described.
